UNITED STATES PATENT OFFICE.

PAUL J. BUNGART, OF OCEANSIDE, NEW YORK.

DRAFTING COMPASS.

Application filed November 18, 1922. Serial No. 601,942.

For a detailed description of the present form of my invention, reference may be had to the following specification and to the accompanying drawing forming a part 5 thereof, wherein—

Fig. 1 is a plan and

Fig. 2 a side elevation of my device;

Fig. 3 is a section of the tripod and

Fig. 4 is a section of the spring-traveller.

10 My invention comprises a drafting compass provided with a radial beam, a central support or tripod for said beam having an expanded base for firm seating on the drawing at the center of an arc to be drawn and a 15 spring-traveller for its outer end which normally holds the pen or other marker slightly elevated above the drawing but may be pressed down to put the pen in contact with the drawing for marking.

20 Referring to the drawing, A represents the radial beam or shaft of the compass being ordinarily made of wood. At its rear or centering end is a supporting tripod B which has an expanded circular base B¹ on 25 the under side of which are the retaining needle points b, b, b. These points will keep the base permanently in position during the drawing operation without any liability of defacing the drawing which frequently occurs when the beam is centered by a single 30 pointed spike. Such a spike makes a large hole in the drawing which becomes further enlarged by the repeated rotations of the spike therein, when many arcs are drawn 35 from the same center. At the center of the base B¹ is a circular opening or window preferably covered with glass or other transparent hard substance on which hair lines cross each other at the exact center and extend over base B. On the upper end of 40 tripod B is swiveled and hinged a block C which carries the usual clamp C¹ for beam A. By means of the swivel joint between 45 B and C the beam may be rotated horizontally and by means of the hinge its outer end may be lifted away from the drawing to enable the draftsman to ink his pen for continuous work without the interruption caused by lifting the compass.

50 At the outer end of the beam A is a second clamp E¹ on the under side of which is the pen or pencil F and back of the pen or pencil is a lug E to which is hinged on a transverse axis the traveller or resilient support D. This traveller has, as appears in Fig. 4, a hollow shaft in which slides a rod or

plunger G carrying a roller G¹ at its lower end and normally pressed outward to the limits permitted by the stops by a coiled spring G². The traveller may be turned up 60 into a horizontal position when desired as shown in dotted lines in Fig. 2. In operation the tripod B will be seated on the drawing at the center of the arc to be drawn, the hair lines aforesaid being at the center of 65 the arc, said base B¹ being firmly seated on the drawing and held against sliding movement by the needle-points. Then the beam A will be turned down till the wheel G¹ of the aforesaid traveller D rests on the paper. 70 The spring G² will still hold pen F a slight distance from the drawing. The traveller will then support the weight of the outer end of the beam and the latter may be freely moved across the paper in an arc centering 75 at the axis of the tripod without any mark being made on the paper. To cause the pen, pencil or marker to mark, a slight pressure downward on the beam will compress the 80 spring G² of the traveller and put the marker into operating position on the drawing. This foregoing arrangement relieves the operator of the burden of upholding the outer end of the beam and enables him to set the marker to the exact point desired 85 with complete accuracy, a screw K being also employed to adjust its radial position.

What I claim as new and desire to secure by Letters Patent is:

1. A drafting compass comprising a centering support having a base of substantial area provided with a central window, anchoring means for said base, a radial beam, and means providing a swivelling and hinging joint between the beam and the support 90 in a position above said window, whereby the view through the window is substantially unobstructed.

2. A drafting compass comprising a centering support, a radial beam, a hinged support member for one end of said beam, said support member having a depending portion swivelled in said support, and means for resiliently supporting the other end of said beam. 100

3. A drafting compass comprising a centering support, a radial beam, a hinging support member for one end of said beam, said support member having a depending portion swivelled in said centering support, a marker 110 at the other end of said beam, and a resilient support for the free end of said beam, said

resilient support normally acting to lift the marker out of contact with the drawing.

4. A drafting compass comprising a centering support having an extended base provided with a central window, anchoring means for said base, a radial beam, means providing a swivelling and hinging joint between one end of the beam, and the centering support in a position above the window, whereby the view through the window is substantially unobstructed, a marker at the other end of said beam, and a resilient support for the beam, said resilient support being positioned contiguous to said marker and normally acting to lift the marker out of contact with the drawing.

5. A drafting compass comprising a centering support, a radial beam having a swivelling and hinging connection at one end of said support, a clamp carried by the other end of the beam and provided with a tube, and a spring-pressed supporting plunger working in said tube, and provided with a supporting roller.

25 6. A drafting compass comprising a beam, a centering support having a base of substantial area provided with a central window, retaining needle points secured to said base, a clamp engaging said beam and hav-

ing a swivelling and hinging contact with said support in a position above the window, whereby the view through the window is substantially unobstructed, a marker carried by the free end of the beam, a tube also carried by the free end of the beam contiguous to said marker, a spring-pressed plunger mounted in said tube and provided with a supporting roller, and means for limiting movement of said plunger.

35 7. A drafting compass comprising a radial beam, an independent centering support to which one end of said beam is hinged and swivelled, a clamp slidably mounted on said beam and provided with a travelling support and a marker, and means for adjusting the relative positions of the marker and the travelling support.

8. A drafting compass comprising a radial beam, an independent centering support to which one end of said beam is hinged and swivelled, a slideable carrier mounted on said beam, a marker and a travelling support independently jointed to said sliding carrier, and means for adjusting the relative positions of the marker and the support 55 along the carrier.
